UNITED STATES PATENT OFFICE.

THOMAS LEAGUE STURTEVANT, OF QUINCY, AND THOMAS J. STURTEVANT, OF WELLESLEY, MASSACHUSETTS.

MULTIPLE OIL-PUMP.

SPECIFICATION forming part of Letters Patent No. 762,103, dated June 7, 1904.

Application filed February 27, 1904. Serial No. 185,573. (No model.)

To all whom it may concern:

Be it known that we, THOMAS LEAGUE STURTEVANT, residing at Quincy, and THOMAS J. STURTEVANT, residing at Wellesley, in the county of Norfolk and State of Massachusetts, citizens of the United States, have invented certain new and useful improvements in Multiple Oil-Pumps, of which the following is a specification, reference being had therein to the accompanying drawings.

This invention relates to a power-actuated oil-feeding device adapted for use with the engines of automobiles or other like devices in the operation of which it is desirable that the parts to be lubricated should automatically receive an unfailing supply of oil.

To this end the improved oiling device comprises an oil-reservoir provided with a series or plurality of power-actuated force-pumps, each of which has a separate discharge pipe or tube to be connected to some part to which it may be desirable to supply the lubricating-oil. The pistons of the several force-pumps are preferably actuated by a single lever which is operated for the suction or filling strokes of said pistons by a cam-receiving movement in any suitable manner from the machine or engine to be lubricated, and the return or forcing strokes of the said pistons are preferably effected by a spring or springs which will give quick forcing movements to said pistons notwithstanding the fact that the shaft carrying the cam for effecting the suction or filling strokes of the pump-pistons will be slowly rotated, as is desirable in effecting such a slow or moderate oil-feeding operation as is required in supplying just enough but not too much oil to the parts to be lubricated. In other words, the speed of rotation of the cam which effects the suction or filling strokes of the pump-pistons will vary according to the speed at which the engine or motor to be lubricated is running and from which the oil-pumps are actuated, so that at a higher running speed more oil will be supplied to the engine or motor than at a lower running speed, and while the suction or filling strokes of the

pumps will thus be variable according to the speed at which the engine or motor to be lubricated is running the forcing strokes of the pump-pistons will always be constant or uniform, owing to the fact that such oil-forcing strokes result from the action of the spring or springs referred to. Thus, however slow the motor may be running, the oil-forcing strokes of the pistons will always be quick and efficient, so that all or nearly all of the oil in the pumps will be ejected out at each forcing stroke. The delivery-tube from each of the pumps is preferably provided with a sight-feed, so that the action of the pumps can at all times be observed, and should the working of any pump fail at any time the sight-feed will immediately reveal this fact.

In the accompanying drawings, Figure 1 is a front view, with the casing partly broken away, of an apparatus embodying the present invention. Fig. 2 is a vertical sectional view of the same, and Fig. 3 is a detail view of the operating mechanism.

Referring to the drawings, 12 denotes a reservoir which is provided at its lower part with a series of pump-cylinders 13, each of which contains a piston 14. Suitably mounted in the casing of the reservoir 12 is a shaft 15, provided with a scroll-cam 16. The shaft 15 may be operated in any suitable manner, as by a slowly-driven belt or by worm or other reducing-gearing, but is shown in the present instance as being provided with a gear-wheel 34, meshing with a suitable gear-wheel 35 on a shaft 36, carrying a ratchet-wheel 17, by which said shaft 36 may be slowly rotated through the medium of the pawl 18, operated by a swinging pawl-carrier 19, which may receive motion in any suitable manner, as from a link or pitman 20 to be connected with any suitable part of the motor-engine to be lubricated.

Mounted in the casing of the reservoir 12 is a bell-crank lever 21, having a sleeve encircling the shaft 36, and the outer or shorter arm of which lever engages the scroll-cam 16. The lower arm of the lever 21 is provided with

a broad blade 22, engaging the several pump-pistons 14, which are suitably notched for the reception of the said blade, and which latter extends through openings 33, formed in the upper portions of the pump-cylinders 13. In their backward or filling movements the pistons 14 retreat far enough so that the cylinders of the pumps may be filled by the oil in the reservoir passing into said cylinders through the openings just referred to. Bearing against the bell-crank lever 21 is a stiff spring 23, which imparts quick oil forcing or feeding movements to the pump-pistons 14 when the short arm of the bell-crank lever 21 falls off from the high point of the scroll-cam 16 into the low part or notch thereof. From this it results that while the suction or filling movements imparted to the pump-pistons 14 from the scroll-cam 16 through the lever 21 will be comparatively slow and will be variable according to the varying speed at which the engine or motor to be lubricated may be running the oil-forcing or oil-feeding movements imparted to said pistons from said spring will always be rapid and constant, so that an efficient oil-forcing operation always results therefrom.

The outlet of each of the pump-cylinders is provided with a spring-pressed ball-valve 24, which is inserted in place from the outer end of the tube forming the pump-cylinder, the opening at the outer end of said cylinder being closed by a plug-screw 25, formed partly hollow for the reception of a spring 26, which forces the ball 24 to its seat. The pistons 14 are inserted in the chambers of the pump-cylinders 13 from the ends of said cylinders opposite that at which the ball valves are located, and the openings through which said pistons are inserted are closed by plug-screws 27.

Each of the delivery-tubes 28 is preferably provided with a glass tube 29, inserted therein, the said tubes 28 being provided with openings affording windows, and through which windows it can be ascertained at all times whether or not all of the pumps are properly working. Communicating with each of the said delivery-tubes 28 is a feed-pipe or oil-conducting tube 33, which is to be connected in any suitable manner to a portion of the engine or motor to be lubricated.

From the foregoing it will be apparent that this invention provides a compact and efficient multiple-pump-power oiling device, which may be located in any suitable or convenient relation to the machine or motor to be lubricated and the various delivery-tubes of which may be connected with the parts to be oiled, so that an unfailing supply of oil will be automatically delivered to said parts. If the multiple-pump oil-feeder be located on the dashboard of an automobile, the proper working of the pumps can be conveniently

observed through the several sight-feed openings while the car is running or without requiring the occupants to dismount, and owing to the fact that the pump-operating devices are inclosed within the oil-reservoir they will themselves be at all times suitably lubricated.

The reservoir 12 is provided with a nozzle or nipple 30, through which oil can be supplied thereto, and for long trips it will be advisable to connect the supply-opening of the said reservoir with a larger reservoir, as 31, connected with the reservoir 12 by a pipe 32.

Having thus described our invention, we claim and desire to secure by Letters Patent—

1. A power-oiler comprising the combination with an oil-reservoir, of a plurality of force-pumps having reciprocating pistons, a scroll-cam for effecting the suction or filling movements of said pistons, a lever actuated from said cam and connected with said pistons, and a spring acting on said lever and serving to impart quick oil forcing or feeding movements to said pistons when the high part of said cam passes the contiguous part of said lever and the latter falls into the notch or low part of said cam.

2. A power-oiler comprising the combination with the reservoir 12, of a series of pump-cylinders 13 in the lower part thereof, a piston 14 for each of said pumps, the bell-crank lever 21 engaging said cam and said pistons, and the co-operating spring 23 for imparting movements to said lever in opposition to those effected by said cam.

3. A power-oiler comprising the combination with the reservoir 12, of a plurality or series of pump-cylinders 13 in the lower portion of said reservoir, a reciprocating piston 14 for each of said pumps, said pistons being notched in their upper sides, the shaft 15, the cam 16 on said shaft, the bell-crank lever 21 one arm of which engages said cam and the other arm of which is constructed to form the blade 22 entering the notches formed in said cylinders, and the spring 23 co-operating with said cam and lever.

4. A power-oiler comprising the combination with the reservoir 12, of a series of pump-cylinders at the lower part of said reservoir and having openings in their upper parts for the entrance of oil, pistons movable in cylinders, means within said reservoir for operating said pistons, spring-pressed ball-valves controlling the outlets from the said pump-cylinders, plug-screws closing the chambers in which the said ball-valves are located, and plug-screws closing the openings to said cylinders through which the said pistons are inserted.

5. The combination of an oil-reservoir, a multiple-cylinder submerged oil-pump inclosed thereby, a cam-actuated lever in said reservoir for forcing back the pistons of said

pumps, and a spring for effecting the oil-forcing strokes of said pistons.

6. In an oil-reservoir, and in combination, a multiple-cylinder and multiple-piston force-pump, an operating-lever for the pistons of said pump, a cam for effecting the suction or filling strokes of said pistons and a spring for effecting the oil-forcing strokes of said pistons.

In testimony whereof we affix our signatures in presence of two witnesses.
